UNITED STATES PATENT OFFICE.

FRANK A. LUNDQUIST AND JOHN A. KROPP, OF CHICAGO, ILLINOIS, ASSIGNEES, BY
MESNE ASSIGNMENTS, TO HENRY S. CONRAD, TRUSTEE.

AUTOMATIC TELEPHONE EXCHANGE.

Application filed April 7, 1921, Serial No. 459,503. Renewed December 15, 1924.

To all whom it may concern:

Be it known that we, FRANK A. LUNDQUIST and JOHN A. KROPP, citizens of the United States of America, and residents of Chicago, county of Cook, and State of Illinois, have invented certain new and useful Improvements in Automatic Telephone Exchanges, of which the following is a specification.

10 Our invention relates to automatic telephone exchanges, and more particularly to connector switches and the arrangements by which such switches are used in making telephonic connections to either private lines 15 or party lines. The object of the invention is to make improvements in the apparatus and circuits for such connections.

The accompanying drawing is a diagram in which the wipers are carried by the well known longitudinal and rotary shaft. This shaft, and other pieces of apparatus to be described, is moved by sylphons, which are pneumatic motors of the diaphragm type. These motors are operated by compressed 25 air flowing from a general supply pipe and are controlled by valves which are normally closed but which may be opened by pressing a projecting pin inward. The structure and 30 function of other devices will be set forth in connection with the description of the operation.

The wires 2 and 3, extend to a previous switch, which may be either a selector or a line switch, and then to a calling station 35 where they are connected together when the subscriber thereat removes his receiver from its hook. When the connector shown in the drawing is seized, a current flows:—battery 40 X—1—2—calling station—3—4—5—6—7—8—9—10—ground—X.

This attracts armature 11 to open valve 12 and permits valve 13 to close. Opening valve 12 permits compressed air to flow from the supply pipe 14 to sylphon 15 which expands to move lever 16 so as to open valve 17. (The supply pipe is marked 14 at other places.) Between the valve 12 and sylphon 15 is a check valve 18 which permits a quick flow of air to the sylphon but retards the exhaust therefrom. This makes sylphon 15 a slow motor which remains expanded during the brief closures of the valve 12 hereinafter to be described.

55 The opening of valve 17 permits air to flow to valve 13 which was previously closed,

and thru pipe 19 and check 19^a to sylphon 20 which acts to turn lever 21 on its pivot 22. The free end of lever 21 is connected thru link 23 with the tail of a pawl 24 which is pivoted to a slide 25. When the lever 21 is moved as previously described, the pawl is turned upon its pivot until it engages a flange on a channel 26, after which the movement of the lever moves the slide until the pawl engages a tooth 27 cut on one flange 65 of the channel.

The channel 26 is pivotally mounted on pins 28 secured at each end, and has cut on its flanges teeth which are spaced as shown in the drawings. The long teeth are 70 represented as being on the near side of the channel, and the short teeth on the far side. When the channel is rocked on its pivots, the teeth are alternately brought into and moved out of the path of the pawl carried 75 in slide 25 and advanced by lever 21. A spring 29 normally holds the channel so that the teeth on the far side are in the path of the pawl. A sylphon 30 acts on the channel to turn it on its pivots against the action of spring 29.

The operations described up to and including engagement between pawl 24 and tooth 27 are automatic operations which occur as a result of the switch being seized by 85 the operation of some other switch. Part of this operation is a short movement of slide 25 which permits springs 31 and 32 to open and remove ground connection from wire 33.

The next thing that occurs is an operation 90 of his dial by the calling subscriber, which operation rapidly breaks and remakes the connection between lines 2 and 3 a desired number of times. Breaking the connection between these lines breaks the circuit for the magnet 1—4, whereupon armature 11 falls back and permits valve 12 to close. But as the valve is quickly reopened by the remaking of the circuit, and as there is a check valve 18, such brief closing of 100 valve 12 does not affect sylphon 15 which continues to hold valve 17 open so the air supply pipe is extended to valve 13.

The vibration of the armature 11 which 105 operates valve 12 without producing any result beyond that valve, opens and closes valve 13 rapidly a succession of times. Such opening of valve 13 permits air to flow thru pipe 34 to an air distributor 35, and thru a branch pipe 36 to sylphon 30 to operate it. 110

In the pipe 36 is a check 37 which makes sylphon 30 a slow motor which remains expanded during rapid vibrations of armature 11, but which contracts as soon as the vibrations cease. This expansion of sylphon 30 turns the channel 26 so as to release pawl 24 from tooth 27 and permit slide 25 to advance till said pawl engages tooth 38.

Inside of the distributor 35 is a plunger 39 having an interior passageway 40, the upper end of which is open and the lower end of which is adapted to register with pipes entering the casing of distributor 35. The plunger 39 is connected to the slide 25 so that each movement of the slide causes a corresponding movement of the plunger. The movement of the slide which brought pawl 24 to tooth 38 also brought the lower end of the passageway 40 to the pipe 41 which leads to the sylphon 42. This sylphon operates the vertical movement of the shaft 43, and is the equivalent of the ordinary vertical magnet in this type of switch. The previously described air pulsations which enter pipe 34, by reason of valve 13 being opened by vibrations of armature 11, flow thru 40 and 41 to cause as many expansions and contractions of sylphon 42 as there are impulses flowing thru magnet 1-4. These operations of sylphon 42 cause corresponding upward steps of shaft 43.

On the termination of the series of impulses just described, the circuit thru magnet 1-4 is closed and the armature 11 remains in attracted position. This cuts the air supply from sylphon 30 and pipe 34. As a consequence, the sylphon 30 contracts and the channel 26 is turned on its pivots to release tooth 38 and permit sylphon 20 to advance slide 25 till pawl 24 engages tooth 44. This is a long step which brings the lower end of passageway 40 to pipe 45 leading to the rotary sylphon 46.

The next thing that happens is another operation of his dial by the subscriber, which results as before in expanding the sylphon 30 and in sending air pulsations to sylphon 46 to turn shaft 43. The expansion of sylphon 30 releases tooth 44 and permits pawl 24 to advance to tooth 47. This is a short step which produced no result other than prepare the apparatus for the next operation.

The rotary operation just described is the one which carries the wipers on shaft 43 to the terminals of the subscriber to be called, as is the ordinary practice. At the termination of this series of impulses, the sylphon 30 contracts as before, and the pawl 24 advances a long step from tooth 47 to tooth 48. This long step carries the passageway 40 from pipe 45 so that no further impulses flowing thru pipe 34 will affect the position of the wipers.

This long step to tooth 48 also brings a

circuit closing head 49 on slide 25 to a position in which it bridges the terminals of "busy tone" and the terminals of wires extending thru condensers 50 to wires 2 and 3. Also, this long step brings insulation 51 to a position in which it shifts spring 6 from spring 7 to spring 52. The spring 7 furnished a ground connection thru spring 10. If the connector has been moved to the terminals of a busy line, then the spring 52 will also furnish a ground connection as follows:—52—53—private wiper 54, and to ground on the busy called line in the ordinary manner.

But if the connector is moved to a non-busy line, then the private wiper finds no ground connection, and the movement of spring 6 from spring 7 breaks the circuit for magnet 1-4. This opens valve 13 and permits air to flow to sylphon 30, which rocks channel 26 and permits pawl 24 to advance from tooth 48 to tooth 55. This is a long step which follows immediately upon the heels of the previous long step from tooth 47. Previously, the long steps came as a result of attracting the armature 11, and the short steps as a result of releasing the armature. From this point on the order is reversed, and long steps come as a result of releasing the armature and short steps as a result of attracting it.

The long step to tooth 55 carries insulation 51 away from spring 6 so that it re-engages spring to remake the circuit for magnet 1-4 and cause the pawl 24 to advance a short step to tooth 56. These steps bring head 49 to the ringing position.

In the lower part of the drawing are shown three sets of bank wires representing three lines, any one of which may be called by a subscriber operating the connector shown. The central set contains three wires and represents a private line. The upper and lower sets each have a fourth wire a permanent ground connection, and these sets represent party lines. It will be assumed that the position to which the wipers move as previously described is the private line.

The wipers being on a private line, and the head 49 being in a ringing position, the circuit from the ringing generator includes contact makers 57—wires 58—springs 59 and 60—contacts 61—49—62—wires 63 and wipers 64 and 65—bank wires 66 and 67—and called station thru the ordinary connections. There is a branch of this thru the relay 68—but the armature of this relay is sluggish, and the ringing current produces no result upon it.

The ringing circuit before described calls the subscriber who removes his receiver. This completes a circuit which excludes the local station ringer as follows:—battery X'—68—69—previously described ringing circuit—70—71—ground—X'.

This attracts the armature 72 and breaks the circuit for the magnet 1-4 at spring 10. Breaking this circuit again opens valve 13 and permits sylphon 30 to expand and release tooth 56 so that pawl 24 may advance to tooth 73. This carries the head 49 from contacts 61-62 to the talking position at contacts 74-75. The movement of the head 49 from 61-62 breaks the circuit for relay 68-71, whereupon the circuit for magnet 1-4 is remade and the channel 26 moves back to its previous position. This permits the pawl to advance to tooth 76, but as this is a short step it affects nothing.

The talking circuit can be readily traced from lines 2 and 3, thru condensers 50 and head 49 to the wipers 64 and 65 which were previously described as having come upon the terminals of the called subscriber. The called station gets its battery from X^2 over connections which will be easily seen by examining the contacts on the head 49.

In the previous description it was assumed that the calling subscriber had moved his wipers to the terminals of a private line represented by the bank wires 66 and 67. It will now be assumed that he moves his wipers to the terminals of the upper party line. This brings his wiper 93 to the terminal of the permanently grounded line 94 at the same time that the insulation 77 on slide 25 engages a lever 78 pivoted at 79 and turns said lever to close two sets of springs. The closure of spring 80 to spring 81 connects ground thru 82 and 53 to the private wiper 54, and this is the same whether the wipers be moved to a private or to a party line. Closing springs 86 and 87 when wiper 93 reaches the permanently grounded line 94 completes a circuit as follows:— X —83—coil 84—85—86—87—88—89—90—91—92—93—94—ground— X .

This attracts armature 95 to open valve 96 and permits air to expand sylphon 97, and this in turn moves lever 98 on its pivot to project the end 99 within a slot in the lower end of channel 26 and thereby lock it against movement. This movement permits a breaking of the ringing circuit at the springs 59 and 60, and as this occurs at the instant when the head 49 reaches the ringing position, it will be evident that ringing does not occur at this point in making a party line connection as it does when the connection is to a private line.

At the time when the head 49 reaches the ringing position, the lower end of passage-way 40 comes opposite the end of pipe 100. In the case of calling a private line, nothing happens as a result of this connection, but in calling some particular person on a party line, the calling subscriber must operate his dial again to get the person desired.

This admits air to pipes 34 and 36. That going to sylphon 30 is without effect as

the projection 99 locks channel 26 against movement, but that going thru pipe 34 reaches pipe 100 and operates sylphon 101 to move ratchet wheel 102, and sylphon 103 to close springs 104 and 105. The sylphon 101 responds by as many expansions and contractions as there are impulses sent to magnet 1-4 by the dial operation, but the sylphon 103 remains expanded during pulsations because of a check valve 106 which makes 103 into a slow motor. The movement of the ratchet wheel 102 opens the connection between springs 90 and 91, but the sylphon 103 bridges the connection between 88 and 92 by way of springs 104 and 105 so that the circuit of magnet 84 remains unaffected.

The contact makers 57 are insulatingly carried on the shaft of ratchet 102 in the same way that wipers are carried on the ratchet shaft 43. When the ratchet wheel 102 is advanced, the contact makers 57 are moved from the regular ringing connection at 107 to one or another of the adjacent variable ringing connections, depending upon how many impulses are sent to the magnet 1-4 by the dial operation.

When the dial operation ceases, armature 11 remains attracted to close valve 13 and cut the air supply from pipe 100. The consequent contraction of sylphon 103 breaks the circuit for magnet 84 and this in turn cuts the air supply from sylphon 97. This lets lever 98 fall back to release channel 26 and to close springs 59 and 60 to their adjacent contacts. This re-establishes ringing connection thru head 49 to the party line, the particular signal sent to the line being determined by the position of the contact makers 57. From this point on the operation is the same as in the case of calling a private line.

What we claim is:—

1. In a telephone switching mechanism, a slide and means for placing it under a strain to move it, an escapement and control therefor for permitting such movement, a plurality of motors, a source of air pressure for operating said motors, and an air distributor operated by said slide and arranged to permit air to flow from the source to the motors in succession.

2. In a telephone switching mechanism, a slide and means for moving it, devices for controlling such movement, motors for moving the switching mechanism, a source of air pressure, and an air distributor moved by the slide to admit air to said motors in succession to cause the operation thereof.

3. In a telephone switching mechanism, a plurality of motors for moving the mechanism, a source of air pressure, an air distributor arranged to admit air to said motors so that they will operate in succession to move the mechanism, and an escapement

controlling the operation of the distributor.

4. In an automatic telephone exchange, wipers for making telephonic connections, contact makers thru which desired ringing connections are made to said wipers, pneumatic motors for moving the wipers in a primary and secondary movement, a pneumatic motor for moving the contact makers, a source of air pressure, and means for connecting said motors in succession to said source.

5. In a switching mechanism arranged to make connections to either private or party lines, motors for moving the mechanism, a progressively movable controlling device for controlling said motors successively, means for continuing the movement of said device after the last motor has operated, and a locking device controlled over a wiper 20 of said switching mechanism for holding the controlling device only when the mechanism engages a party line.

6. The combination with a switching mechanism, a plurality of party lines, pneumatic devices for moving the mechanism to engagement with one of said lines, and variable ringing connections, of means by which the moved parts are isolated from ringing connections when one of said lines is engaged, contact makers, pneumatic devices for moving them to engagement with a desired one of the ringing connections, and automatic means for extending the ringing connection to moved parts of the mechanism when the desired connection is made by the contact makers.

7. A source of ringing current, a ringing connection having on one end movable contact makers normally connected to said source and having on the other end stationary terminals, a contact head movable to engagement with said terminals, and means operated during such movement of said head for breaking the ringing connection.

45 8. A source of ringing current, a ringing connection having on one end contact makers normally connected to said source and having on the other end stationary terminals, a movable part serving to connect a telephone line to said terminals, means associated with such movement of said part for breaking the ringing connection, other sources of ringing current, means for moving said contact makers to any one of the other of said sources, and means by which upon said contact makers coming to rest upon any one of the other of said sources the previously broken ringing connection will be remade.

60 9. A series of sources of ringing current, contact makers thru which any one of said sources may be connected to a telephone line, a magnet serving to control such connection, and a pair of springs for completing an electrical circuit for said magnet

when said contact makers are in normal position and for opening said circuit as a result of said contact makers being moved from normal position.

10. Wipers, means for moving them step by step to a telephonic connection, a plurality of sources of electrical energy, means for connecting said sources successively to said wipers, a device for controlling both said means, and means for simultaneously locking said controlling device and breaking the connection between the wipers and one of said sources.

11. Wipers, means for moving them to a telephonic connection, a plurality of sources of ringing current, means for connecting said sources successively to connections leading to said wipers, means by which the last named connections are broken during the successive connecting operation, and means by which the connection from a source to the wipers is automatically re-established upon a pause occurring in the successive connecting operation.

12. Wipers movable by successive steps to a desired telephonic connection, a contact head movable by successive steps to different sources of electrical energy, a sub-division of one of said sources into different parts, contact makers movable to any one of said sub-divisions, pneumatic motors for causing all of said movements, a source of air pressure, and a magnet serving in succession to control the flow of air to and from all of said motors.

13. In a connector switch having primary and secondary movements, primary and secondary air motors for operating the switch, an air pipe having outlets to said motors, a source of air pressure, means for connecting said source to said pipe, and a device in said pipe for successively opening said outlets to cause said motors to operate in succession.

14. In a connector switch having primary and secondary movements, primary and secondary air motors for operating the switch, an air pipe, said motors having air connections to said pipe, means for delivering a series of air pulses to said pipe, and a device in said pipe for delivering the first of said series of air pulses to the connection leading to the primary motor and the second of said series of air pulses to the connection leading to the secondary motor to cause the successive operation of said motors.

15. In a telephone system, connector switches for establishing connections with single and party lines, pneumatic motors for operating said switches to establish such connections, said single and party lines terminating indiscriminately with respect to each other in the banks of said switches, a plurality of sources of ringing current, contact makers for selecting any one of said

sources of ringing current, said contact makers normally in engagement with the particular one of said sources of ringing current which is adapted to signal said 5 single lines and a pneumatic motor for operating said contact makers step by step to select the desired ringing current when a party line is called.

16. In a telephone system, connector switches for establishing connections with either single or party lines, said single and party lines terminating indiscriminately with respect to each other in the banks of said switches, and pneumatic motors for 15 operating said switches to establish such connections.

17. A series of sources of ringing current, contact makers through which any one of said sources may be connected to a telephone line, a magnet serving to control such connection, a pair of normally closed springs for completing an electrical circuit for said magnet when said contact makers are in 20 normal position, said springs opened as a result of said contact makers being moved 25 from normal position, and a pair of normally opened springs closed during the movement of said contact makers for maintaining said circuit for said magnet uninterrupted during the movement of said contact 30 makers.

18. In a switching mechanism arranged to make connections to either private or party lines, pneumatic motors for moving the mechanism to establish such connections, a controlling device for controlling said 35 motors, and a locking device operated only when the mechanism engages a party line for locking said controlling device.

40 19. A source of ringing current, a ringing connection having on one end movable contact makers normally connected to said source and having on the other end stationary terminals, a contact head moved step by step by a pneumatic motor and an escapement to engagement with said terminals, and a pneumatic motor operated as a result of such movement of said head for breaking the ringing connection.

45 20. A source of ringing current, a ringing connection having on one end contact makers normally connected to said source and having on the other end stationary terminals, a movable part serving to connect a telephone to said terminals, a pneumatic device associated with such movement of said part for breaking the ringing connection, other sources of ringing current, a pneumatic motor for moving said contact makers to any one of the other of said sources, and means in response to said contact makers coming to rest upon any one of the other of said sources for remaking said previously broken ringing connection.

50 21. Wipers, pneumatic motors for moving

said wipers step by step to a telephone connection, a plurality of sources of electrical energy, a pneumatic motor for connecting said sources successively to said wipers, an escapement and an air distributer for controlling said pneumatic motors and means for simultaneously locking said escapement and said air distributer and breaking the connection between the wipers and one of said sources.

70 22. Wipers, pneumatic motors for moving said wipers to a telephonic connection, a plurality of sources of ringing current, a pneumatic motor for connecting said sources successively to connections leading to said wipers, means by which the last named connections are broken during the successive connecting operation, and means by which the connection from one of said sources to the wipers is automatically re-established 80 upon a pause occurring in the successive connecting operation.

75 23. In a connector switch having access to both party lines and single lines, a local switching device occupying different positions in succession during the operation of said connector in selecting and establishing a talking connection with a called line, means for automatically moving said device to ringing position when any line is connected with, a ringing circuit automatically established in ringing position to signal the connected line if such line is a single line, means for automatically opening the ringing circuit if the connected line is a party line, and a ringing current selecting device then 90 operable for selecting the proper ringing current to signal the desired station.

95 24. In a telephone system, two classes of subscribers' lines, private normal conductors associated with said lines, a connector switch having bank contacts in which the said conductors terminate, a private wiper in said connector adapted to engage only the said contacts associated with the lines in one class, another private wiper in said connector adapted to engage the said contacts associated with the lines of both classes, means for operating said connector to select 100 a called line in either class, two kinds of ringing equipment associated with said connector, and means under control of the first private wiper for putting one or the other of said equipments in use dependent on the class in which the called line belongs.

105 25. In a telephone system, two classes of subscribers' lines, private normal conductors associated with said lines, a connector switch having bank contacts in which said conductors terminate, a private wiper in said connector adapted to engage only the said contacts associated with the lines in one class, another private wiper in said connector adapted to engage the said contacts associated with the lines in both classes, means 110 115 120 125 130

- for operating said connector to select a called line in either class, means for signalling the called line immediately if said line belongs to one of said classes, and means controlled over said first wiper to signal the called line only after an interval if said line belongs to the other of said classes.
26. In a telephone system, two classes of lines, two digit telephone numbers assigned to the lines of one class, three digit numbers assigned to the lines in the other class, an automatic connector switch responsive to the calling of a two digit number to call a subscriber on a line in the first class and responsive to the calling of a three digit number to call a subscriber on a line in the second class, and ringing equipment automatically started in each case when the calling number is completed to signal the called subscriber.
27. In a telephone system, private or individual lines and party lines, an automatic connector switch, means whereby a calling subscriber can operate said connector in accordance with desired telephone numbers to connect with desired ones of said lines, and ringing equipment automatically responsive after two digits have been called to signal the called subscriber in case such subscriber has a private line, and automatically responsive after three digits have been called to signal the called subscriber in case such subscriber is on a party line.
28. In a telephone system, a party line connector having primary and secondary motors, an auxiliary ringing current selecting switch individual to said connector, a pneumatic motor for operating said switch, a line relay in said connector, and means for placing said motors under control of said line relay.
29. In a telephone system, a party line connector having primary and secondary motors, an auxiliary ringing current selecting switch individual to said connector, a pneumatic motor for operating said switch, a line relay in said connector, and means for placing said motors successively under control of said line relay.
30. In a telephone system, a combined individual and party line connector switch pneumatically operated to connect with individual and party lines, said switch having facilities for performing different characteristic ringing operations depending on the kind of line connected with, and means in said switch automatically responsive when a line is connected with for determining the character of the ensuing ringing operation.
31. In a telephone system, a combined individual and party line connector switch having two sets of test wipers, individual and party lines accessible to said switch, private normal conductors for the party lines terminating in the bank accessible to only one of said wipers, and individual and party lines private normal conductors terminating indiscriminately with respect to each other in the bank accessible to the other of said wipers.
32. In a telephone system, a combined individual and party line connector switch having four sets of wipers, individual and party lines terminating indiscriminately with respect to each other in the banks and accessible to said switch through said wipers, private and line normal conductors for the individual lines terminating in the banks accessible to only three of said wipers, and private and line normal conductors for the party lines terminating in the banks accessible to all of said wipers.
33. In a telephone system, a combined individual and party line connector switch having wipers, individual and party lines terminating indiscriminately with respect to each other in the banks and accessible to said switch through said wipers, four sets of terminals for each line, two of said sets of terminals of each line used for talking purposes, the other two sets of terminals of party lines used for testing purposes, and only one of the other of said two sets of terminals of the individual lines used for testing purposes, the last set of terminals of the individual lines being left dead.
34. In a telephone system, connector switches for establishing connections with single or party lines, pneumatic motors for operating said switches to establish such connections, a plurality of sources of ringing current, and means for selecting a desired one of said sources of ringing current.
35. In a telephone system, a combined individual and party line connector switch for establishing connections with either individual or party lines, and pneumatic motors for operating said switches to establish such connections and signal any desired party on the line.
36. In a telephone system, connector switches for establishing connections with individual or party lines, said individual and party lines promiscuously interspersed with respect to each other in the banks of said switches, means whereby a calling subscriber can operate said switches in accordance with desired telephone numbers to connect with desired ones of said lines, and ringing equipment automatically responsive after two digits have been called to signal the called subscriber in case such subscriber has an individual line, and automatically responsive after three digits have been called to signal the called subscriber in case such subscriber is on a party line.
37. In a telephone system, connector switches for establishing connection with individual or party lines, said individual

and party lines promiscuously interspersed with respect to each other in the banks of said switches, and means for operating said switches to complete connections with the 5 terminals of called lines and applying ringing current thereto responsive to either two or three digits.

38. In an automatic telephone exchange, wipers for making telephonic connections, 10 contact makers through which any one of a plurality of ringing connections are made to said wipers, a pneumatic motor for moving said wipers in a primary movement, a second pneumatic motor for moving said 15 wipers in a secondary movement, a third pneumatic motor for moving said contact makers, a source of air pressure, and a distributor for connecting said motors in succession to said source.

39. In a telephone system, a pneumatically operated connector switch for completing connection with the terminals of a called line and applying ringing current thereto responsive to either two or three digits.

40. In a telephone system, subscribers' 25 lines divided into two classes, a connector switch having wipers for completing a telephonic connection to said lines, a pneumatic motor operated in response to the first set 30 of impulses transmitted to said connector for moving said wipers in a primary movement, a second pneumatic motor operated in response to the second set of impulses 35 transmitted to said connector for moving said wipers in a secondary movement into engagement with the bank terminals of the called subscriber's line corresponding to said sets of impulses, ringing current, means for applying ringing current to said called line 40 after said two sets of impulses have been transmitted if said line is in the first class, and means for preventing the application of

ringing current to said line until a third set of impulses have been transmitted to said connector if said line is in the second class. 45

41. In a telephone system, a connector switch adapted to be pneumatically operated to establish connections with individual or party lines, said lines divided into groups, said individual and party lines promiscuously 50 interspersed with respect to each other in the bank of said switch, means for operating said switch vertically to select a group of lines, means for rotating said switch to select a line in the selected group, a plurality 55 of sources of ringing current, and means for selecting a desired one of said sources of ringing current.

42. In a telephone system, a connector switch for establishing connections with individual or party lines, said individual and party lines promiscuously interspersed with respect to each other in the bank of said switch, a plurality of sources of ringing current, a pneumatic motor in said switch, 60 and means for operating said motor for selecting a desired one of said sources of ringing current.

43. In a telephone system, a connector switch adapted to be operated by pneu- 70 matic motors to establish connections with individual or party lines, said individual and partly lines promiscuously interspersed with respect to each other in the bank of said switch, said switch having facilities for 75 performing different characteristic ringing operations depending on the kind of line connected with, and means in said switch automatically responsive when a line is connected with for determining the character of 80 the ensuing ringing operation.

FRANK A. LUNDQUIST.
JOHN A. KROPP.
